WOOD GRAINING APPARATUS

Roy E. Woolens, Detroit, Mich., assignor to
 Parker-Wolverine Company, Detroit, Mich., a
 corporation of Michigan

Application March 1, 1937, Serial No. 128,475

7 Claims. (Cl. 101—35)

This invention relates to wood graining apparatus. More particularly it relates to a novel form of wood graining machine primarily designed to rapidly and efficiently reproduce a simulation of wood grain upon the curved surface of a molding or other similar article.

As is well recognized, the reproduction of wood grain upon sheet metal or other similar articles has long been practiced. It has heretofore been conventional in the reproduction of wood grain upon articles having arcuately curved or irregular surfaces, to apply the wood graining ink thereto by means of a soft resilient transfer roll usually formed of gelatin or similar composition. While the rolls most commonly utilized for the purpose of transferring an imitation wood grained surface decoration to an article are sufficiently resilient so that a certain amount of surface irregularity may be tolerated, it has been found that the elasticity of the gelatinous rolls now available is insufficient to cover the entire surface of a molding or a similar article which has an extremely sharply curved arcuate surface. It is a primary object, therefore, to provide a mechanism which will reproduce an imitation of wood grain upon the curved surface of a molding in a single operation thus limiting the number of hand operations which must necessarily be performed and doing away to some substantial extent with the touch-up operations heretofore required.

The present invention contemplates the provision of a pair of wood graining units arranged upon axes at right angles to each other. Each of the wood graining units includes a soft resilient gelatinous transfer roll adapted to engage the surface of a molding to be finished. Means are utilized for driving the rolls in synchronism in order that each will apply a certain predetermined portion of wood graining to the surface of the article under treatment. The wood grain designs used upon the hard metal electrolyte rolls which are utilized for transferring the ink to the gelatinous rolls are likewise synchronized in order that the grained surface area applied by one roll will accurately match the grained surface applied by the other roll thus virtually eliminating any line of demarcation between the particular zone woodgrained by one unit and the zone of surface woodgrained by the other unit.

The invention still further contemplates means for accurately adjusting the relative positions of the respective wood graining units without altering the synchronized operation thereof in order that the zone to which woodgraining is ap-

plied by one of the units may be accurately controlled to mate accurately with the zone to which wood graining is applied by the other of said units. The invention further contemplates the provision of novel mechanism for urging the article to be finished into engagement with the respective rolls in order that an accurate mating of the zones upon which the woodgraining is produced may be obtained.

The present invention contemplates the provision of an idle roll adapted to guide and support the molding to which the graining is to be applied and a control pedal is utilized for the purpose of accurately controlling the position of this feed roll in order that the extent to which the molding may be urged into engagement with one of the gelatinous rolls may conveniently and accurately be controlled.

The invention still further contemplates the provision of a construction primarily adapted for woodgraining moldings which construction embodies two separate wood graining units which wood graining units are operated in synchronism and still further contemplates the provision of accurate and easily controlled means for adjusting the position of one of the units with respect to the other without in any way disturbing the synchronous operation thereof.

Many other and further objects, advantages, and features of the present invention will become clearly apparent from the following specification when considered in connection with the accompanying drawings forming a part thereof.

In the drawings:

Figure 1 is a side elevational view with parts in section and parts broken away illustrating one embodiment of the apparatus.

Fig. 2 is a top plan view on a reduced scale of the work table surface illustrating in general the configuration thereof.

Fig. 3 is an enlarged fragmentary side elevation view with parts in section and parts broken away showing the two associated and synchronized wood graining units and illustrating the means by which these units are simultaneously driven.

Fig. 4 is an enlarged fragmentary sectional view taken substantially on the line 4—4 of Fig. 3 illustrating in further detail the relative positions of the separate wood graining units and the manner in which the same are mounted and interconnected.

Fig. 5 is a fragmentary perspective view of one form of molding which may conveniently be

wood grained by the apparatus of the present invention.

The specific embodiment of the invention illustrated in the drawings includes generally a supporting table or framework 10 which may conveniently be formed from any suitable construction to provide a rigid support for the apparatus as a whole. This table or framework 10 has bearings which serve to provide a pivotal mounting 11 for tabletop 12 in order that this tabletop as a whole may be bodily swung to the desired inclination depending upon the particular type of molding to which the wood graining is to be applied, as will be more clearly understood hereinafter. The adjustment of the inclination of this tabletop may play a very important part in the adaptation of the apparatus herein described to moldings of a substantially varying form and surface curvature.

20 The body portion of the table 10 serves to provide a rigid support for a housing 15 which may conveniently be formed of a casting of unitary integral structure, if desired. This housing 15 is provided with two pairs of respectively axially aligned bearings 16 and 17, respectively. The bearings 16 serve to provide a mounting for a drive shaft 18 and the drive shaft 18 carries an etched metal wood graining roll 19 locked thereto in driving relation, between the bearings 16.

25 The lower end of the drive shaft 18 has a bevel pinion 20 secured thereto which through a bevel gear 21 connects the drive shaft in driving relation with a shaft 22 driven by a suitable electric motor 23 which motor may be conveniently 30 mounted on the table 10. The upper end of the drive shaft carries a bevel gear 26 which meshes with a bevel gear 28 serving to drive a short stub shaft 29 which is journaled for rotation in a suitable support member 30 rigidly connected to 35 the upper portion of the housing 15. The use and function of this apparatus will be more clearly understood from the following description.

A shaft 35 is journaled for rotation in the bearings 17 and has secured thereto a gelatinous transfer roll 36 which frictionally engages the surface of the roll 19. The roll 19 may have the surface thereof engraved or etched in the manner in which photogravure plates are produced in order that a plurality of relatively minute recesses will be formed therein which recesses serve to retain ink applied to this roll by suitable conventional means such as are commonly used in this general art. A scraper or doctor blade 55 (not shown) is mounted in the housing 15 and has the edge thereof in engagement with the roll 19 in order to scrape the surplus ink therefrom before this roll comes into contact with the gelatinous transfer roll 36. As is well understood in apparatus of this general character, the transfer roll 36 will serve to remove the minute bodies of ink from the surface of the etched roll 19 and carry this ink to apply the same to the article upon which it is desired to produce the wood grain. The gelatinous transfer roll, as is conventional in the art, likewise has a doctor blade (not shown) associated therewith which serves to maintain the surface of the roll clean for the reception of ink from the etched roll 19.

70 The support member 30 has an upstanding projection 31 formed integrally thereon, which projection has an aperture therethrough which serves not only to provide a bearing for the stub shaft 29 but serves the purpose of providing a 75 pivotal mounting for a casting 39 which serves

to support a housing member 40 containing the second wood graining unit. This housing member 40 has a shaft 41 journaled therein which shaft serves to carry a gelatinous transfer roll 42 similar in construction to the gelatinous transfer roll 36 described above.

The housing 40 also serves to provide bearings for a shaft 45 on which is mounted a wood graining cylinder 46 similar in construction to the wood graining cylinder 19 described above. Suitable gears 49 and 50 may be keyed to the shafts 45 and 41, respectively, in order to insure that the rolls 46 and 42 will be driven synchronously.

The shaft 45 extends through the wall of the housing 40 and is provided at its outer end with a sprocket wheel 52 which is connected by means of a suitable sprocket chain 53 with a sprocket wheel 54 keyed to the end of the stub shaft 29. Inasmuch as has been explained above, the stub shaft 29 is driven by the drive shaft 18 which 20 serves to drive the first wood graining cylinder 19, it will be apparent that the second wood graining cylinder 46 is likewise synchronously operated with the first mentioned wood graining cylinder. Consequently, it will be readily appreciated that the gelatinous transfer rolls 36 and 42 will likewise be driven in synchronism. Inasmuch as the housing 40 is supported for pivotal movement about the shaft 29, it will be readily appreciated that this housing may be pivotally 30 moved about the axis of this shaft without in any way disturbing the synchronous drive through the sprocket chain 53. Consequently, the relative vertical position of the transversely extending gelatinous transfer roll, may be accurately regulated without materially interfering with the synchronous operation thereof with respect to the gelatinous transfer roll 36.

The housing 40 has an operating link 60 pivotally connected thereto at the point 61 which operating link has its lower end pivotally connected to a fitting 64 slidably mounted on a vertically extending operating rod 65. The operating rod 65 is pivotally connected at its lower end to a spring pressed foot pedal 66 which is preferably 45 constantly urged upwardly by means of a compression coil spring 67. A suitable resilient lost motion connection between the actuating rod 65 and the fitting 64 is provided by means of compression coil springs 67 surrounding the shaft 65 50 on either side of the fitting 64. The lower end of the lower compression coil spring 67 may abut against a projection 68 formed integrally with the housing 15 and the upper end of the upper compression coil spring 67 may be confined by a 55 pair of lock nuts 70 threadably secured on the end of the operating rod 65.

From the foregoing, it will be readily appreciated that as the foot pedal 66 is depressed, the fitting 64 will be resiliently moved downwardly 60 carrying with it the link 60. Inasmuch as the link 60 is pivotally connected to the housing 40, it will be readily understood that the housing 40 will be bodily swung about the axis of the stub shaft 29 and moved downwardly toward the work as will hereinafter be explained in detail.

A work feeding roll 71 is journaled for free rotation upon a pin 72 which pin is carried by a slide 73 mounted for transverse reciprocatory movement in a guideway 74 rigidly supported by main frame 10. The slide 73 has its lower surface recessed to receive one arm of a bell crank 75 which bell crank is pivotally mounted upon the main frame 10 at the point 76. The lower 75

end of the bell crank arm 75 is pivotally connected to the fitting 64. Consequently, it will be seen that upon downward movement of the operating shaft 65, the idle fed roll 71 will be moved 5 forwardly toward the peripheral surface of the gelatinous transfer roll 36 and, as has been explained above, downward movement of the actuating rod 65 likewise serves to move the housing 40 downwardly consequently, bringing the gelatinous transfer roll 42 into engagement with work carried by the idle roll 71.

It will be noted that the horizontal axis of the wood graining unit has the etched metal roll thereof, which is mounted on the shaft 45, positioned in a bearing block 80, the position of which may conveniently be adjusted by means of the adjusting screw 81. The opposite end of the shaft 45 may be conveniently positioned by means of an adjustable yoke or arm 82 secured to the housing 40 by means of a bolt 83. Consequently, it will be appreciated that by adjusting the screw 81 and the yoke 82, the working pressure between the etched roll 46 and the gelatinous roll 42 may be accurately regulated. 20 It will be appreciated that this adjustment need be effected only through an extremely narrow range and consequently the intermeshing of the gears 49 and 50 is not materially affected thereby. It will likewise be appreciated that a similar 25 construction may be employed in connection with the etched roll 49 and gelatinous roll 36 if desired. Such adjustments have been found desirable in some instances because in order to get a satisfactory reproduction, the working pressure between the etched roll and the gelatinous roll has in particular installations been found extremely important.

From the foregoing description, it will be readily apparent that a curved surface molding 90 may rapidly and conveniently be wood grained by means of the machine of the present invention. In order to reproduce wood grained images upon the molding 90, the table 12 is first adjusted to a position such that it serves to support the base 40 portion of the molding to which it is desired to apply the wood grain. The wheel 71 has a peripheral configuration adapted to smoothly engage the rear side of the molding 90 in order to feed the same into contact with the rolls. The apparatus as a whole is preferably driven continuously and the molding 90 may be placed upon the feed roll 71 and it will be understood that when the pedal 66 is in upward position, the molding mounted on the feed roll will be in a 45 position out of contact with the both of the rolls 42 and 36. The pedal 66 may then be depressed which movement will through the spring 67 transmit downward force to the fitting 64 which 50 downward force will be somewhat cushioned due to the lost motion connection provided by the springs 67. As the fitting 64 is moved downwardly, it will simultaneously effect downward movement of the entire housing 40 bringing the gelatinous transfer roll 42 into contact with a 55 portion of the upper curved surface of the molding 90 and at the same time will, through the bell crank arm 75, serve to move the feed roller 71 upwardly to bring the face portion of the molding into contact with the gelatinous roll 36. 60 It will be clear that as the pressure upon the pedal 66 is increased, the housing 40 will be moved downwardly thus deforming the surface of the gelatinous roll 42 to cover a substantial area of the curved surface of the molding. The 65 pressure on the foot pedal 66 may be maintained 70

in such a manner that the zone to which wood graining is applied by the roll 36 will mate with the zone to which wood graining is applied by means of the roll 42. Inasmuch as the pressure on the foot pedal may be very accurately controlled, the molding 90 may have wood graining applied thereto in a single continuous operation without any overlapping or space between the zones acted upon by the transfer rolls. 5

It has been found that these zones can be 10 mated sufficiently accurately in practice so that wood grain of one zone will constitute a virtual continuation of the pattern formed by the wood grain of the other zone. In order to obtain best results, it has been found desirable to utilize 15 matched wood grain rollers whereby the pattern formed by one roll will mate clearly with the pattern formed by the other and constitute a substantial continuation thereof thus virtually obliterating any line of demarcation between the 20 respective zones.

It will be readily appreciated that although but one specific embodiment of the invention has been illustrated and described herein, many other and various modifications thereof falling within the 25 scope of the invention as defined in the subjoined claims will become clearly apparent to those skilled in the art.

I claim:

1. In a machine for wood graining molding, a 30 pair of transfer rolls, means for supporting a molding to be grained with respect to said rolls, and means for effecting movement of one of said rolls and said supporting means to bring said rolls simultaneously into engagement therewith. 35

2. In a wood graining machine, means for supporting a molding to be wood grained, a pair of transfer rolls for applying wood graining thereto, one of said transfer rolls adapted to apply wood graining to a portion of the surface of said molding, the other roll serving to apply wood graining to an adjacent portion of the surface thereof, means for urging one of said rolls into engagement with the work, means for moving the work into engagement with the other of said rolls and 45 means for driving said rolls in synchronism. 40

3. In a machine for wood graining moldings having curved surfaces, a pair of wood graining units each including a metallic wood graining roll and a resilient transfer roll, means for mounting 50 one of said units for pivotal movement with respect to the other, and means for driving said units in synchronism.

4. In a machine for wood graining moldings, a pair of wood graining units each comprising a metallic wood graining roll and a resilient transfer roll, 55 an idle roller adapted to support a molding to be wood grained, means for moving said idle roller toward one of said transfer rolls, and simultaneously actuated means for moving the other transfer roll toward said idle roll.

5. Apparatus for applying wood graining to moldings including in combination a pair of wood graining units each including an etched metal wood graining roll and a resilient transfer roll, 65 the axes of the rolls of one unit being substantially inclined to the axes of the rolls of the other unit, one of said units being operated for pivotal movement with respect to the other and a motor serving to drive all of said rolls in synchronism. 70

6. Printing apparatus including a pair of transfer rolls, one of said rolls being bodily movable with respect to the other, a work supporting member movable to force an article to be printed into engagement with one of said transfer rolls 75

and means for moving the other of said transfer rolls into engagement with the article to be printed.

7. Printing apparatus including a pair of transfer rolls, one of said rolls being bodily movable with respect to the other, means for driving said rolls in synchronism, a movably mounted work

supporting member, means for actuating said member to force work carried thereby into engagement with one of said rolls into engagement with the article to be printed and a member for simultaneously actuating said two last mentioned means. 5

ROY E. WOOLENS.
